UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING-MACHINE.

1,363,682.

Specification of Letters Patent. Patented Dec. 28, 1920.

Application filed December 11, 1918. Serial No. 266,193.

To all whom it may concern:

Be it known that I, JESSE A. B. SMITH, a citizen of the United States, residing in Stamford, in the county of Fairfield and 5 State of Connecticut, have invented certain new and useful Improvements in Typewriting-Machines, of which the following is a specification.

This invention relates to typewriting machines, and is herein illustrated as applied to a machine of the general type disclosed in the patent to Wernery and Smith, No. 1,132,055, wherein the usual Underwood platen is adapted to be lifted in the carriage 10 to enable a work-sheet web to be drawn substantially straight beneath the platen.

One object of having the platen thus liftable is to enable carbon sheets to be readjusted between the work-sheets without 15 reinserting the carbon sheets, with the result that long webs of paper may be readily used as work-sheets. For handling such webs, it is often convenient to have them in rolls. There is some difficulty in preserving 20 the alinement of separate webs, and of insuring that, when drawn off from the rolls, the webs do not slip over each other or over the platen during the act of line-spacing. This invention relates to an improvement in 25 the means for producing a slack in the webs by unwinding the same from the rolls, preparatory to the line-feeding operations, so that the platen at each line-spacing operation will not have the burden of starting the 30 supply roll or rolls into rotation.

To enable the more convenient handling of such webs and the preserving of their alinement, I have found it advantageous to utilize the carbon-paper-carriage of said 40 Wernery and Smith patent by providing thereon a clamp which is adapted to automatically grip and release the webs.

To enable a slack to be produced between the rolls and the platen after the webs are 45 alined at the printing point, an oscillation of the carbon-paper-carriage may cause the clamp to seize the webs and to then hold them seized when the carbon-paper-carriage is drawn forward, but to release them during the backward movement of the carriage. 50 This slack may be taken up during subse-

quent line-spacing operations. The clamp may be also automatically released by drawing forward upon the webs when seized by the hand.

To enable the mechanism to be used in connection with forms of varying lengths, and on webs of various widths, the clamp or its controlling means or both may be adjustably mounted.

Other features and advantages will hereinafter appear.

In the accompanying drawings,

Figure 1 is a perspective view of an Underwood fan-fold machine of the type referred to, showing my invention as applied thereto.

Fig. 2 is a fragmentary perspective, showing the relationship of the clamp to the web, and the carriage upon which it is mounted.

Fig. 3 is a perspective view of the clamp-controlling device.

Fig. 4 is a sectional side view, largely diagrammatic, showing the clamp effective with the platen thrown upward after writing a form.

Fig. 5 is a similar view showing the ends of the webs gaged, the clamp ineffective, and the carbon carriage started on its way rearwardly, so that it may again pick up the webs.

Fig. 6 is a fragmentary view showing the carbon carriage of Fig. 5 at the end of its movement and seizing the webs.

Fig. 7 is a view similar to Fig. 6, with the webs fully seized.

Fig. 8 is a perspective view, showing most of the parts of Fig. 2, but seen from the opposite side and showing additional parts.

Fig. 9 is a diagrammatic sectional side view, showing the carbon carriage pulled forward to produce a slack after the clamp has become effective, as in Fig. 5.

Fig. 10 is a view similar to Fig. 9, but with the carbon carriage pushed rearwardly from the position seen in Fig. 9, thus bringing the slack adjacent the rolls so that it may be drawn upon smoothly during the subsequent line-spacing operations.

In the usual Underwood fan-fold typewriting machine of the kind referred to above, 100 types 1 on type-bars 2 print upon a work-sheet 3 passed around the platen 4, said

55

platen being rotatably mounted in the swing frame 5, so that it may be swung up to the position seen in Fig. 4, thus permitting the work-sheet 3 to be drawn along as part of a 5 web 6 wound around a roll 7. In addition to the work-sheet 3, there are shown sheets 8 and 9 for receiving carbon copies lying between the work-sheet 3 and the platen 4, and which are drawn from rolls 10 and 11, 10 respectively.

The platen 4 is adapted to be rotated in either its normal position or in its lifted position by means of the usual line-space handle 12, which, through the usual slide 15 13, is adapted to turn the ratchet wheel 14, said ratchet wheel being connected by the usual pinions 15 and 16 to the axle of the platen, there being an idle pinion (not shown). To enable the platen 4 to 20 be swung up in its frame 5, the frame is provided with a handle 17 fast thereto, which is normally caught down by a spring-pressed latch 18 adapted to swing upon the body 19 of the carriage. When pressing 25 rearwardly the latch 18, the typist can draw on the handle 17, thereby swinging the swing frame 5 around the axle 20 to the Fig. 4 position. When in this position, the webs 3, 8 and 9 may be seized by the fingers and 30 drawn along and gaged against the usual adjustable end gage 21, said gage being mounted on an extension 22 of the front paper-table 23, said table being provided with the adjustable side gages 24.

With the webs and platen in the Fig. 4 position, the typist may draw the webs to the Fig. 5 position, in which they are gaged against the gage 21, and then the typist may push the usual carbon-paper-carriage 25 40 rearwardly by pressing upon a handle 26, thus carrying rearwardly the carbon sheets 27 and 28, which are held to the usual clips 29 upon the carbon carriage between which the webs 8 and 9 are threaded.

The typist pushes the carbon carriage rearwardly in the manner described, sliding it upon the rails 30, which form an extension of the carriage frame 19, until the carbon carriage 25 carries the upper end 31 of 45 a clamping bar 32 against the over-hanging stop arm 33 of an adjustable bracket 34. When the end 31 strikes the arm 33, the clamping bar 32 swings about its pivot 35, so that a horizontal clamping arm 50 55 36 on the bar 32 will slide over the surface of the top web 9 and slip into a depression 37 of a stiff spring clamping jaw 38, which is fast to the carbon-paper-carriage 25, thus seizing or pinching the webs 55 between the arm 36 and the jaw 38. The spring 38, it will be noted, is parallel to the rails 30 and is formed of a bent-over spring having a downwardly turned free end 38^a to enable the roller 36 to ride up over it.

The pivot 35 is fast in an upper arm 39

of a bracket 40 to which the spring jaw 38 is riveted, said bracket being provided with an arm 41 extending behind the usual side plate 42 of the carbon-paper-carriage 25, so that it may be screwed thereto by means of a 70 thumb screw 43, which passes through a slot 44 in the arm 41 to enable the clamp to be adjusted to the desired width of web.

When the carbon-paper carriage is pushed rearwardly until the end 31 strikes the arm 75 33, work-sheets or webs are clamped between the arm 36 and the jaw 38 by the swinging of the bar 32. The carbon-paper carriage is arrested almost immediately after the top 31 strikes the arm 33, because the swinging of 80 the bar 32 around its pivot 35 carries a stop-arm 45 thereon against the flat top 46 of the bracket arm 39, which serves to limit the throw of the clamp bar 32 and thus serves as a stop to arrest the carbon-paper carriage. 85

In order to be able to vary the position at which the carbon-paper carriage is thus arrested, the bracket 34 is provided with a clamp 46^a having a finger-piece 47, which screws into a plate 48 loosely embracing the 90 flange of the rail 30, the end of the finger-piece itself bearing against a plate 49, which directly engages the flange. When the clamp 36 has thus seized the webs 3, 8 and 9, the carbon carriage is arrested. The typist 95 may then throw the swing frame and platen 4 into the Fig. 9 position. With the parts in this position, the written-on form will stand at just the right position to be detached by drawing the web across the usual knife 62. 100 Then the typist may draw forwardly the carbon-paper carriage by means of the handle 26, thereby drawing the webs forwardly since they are clamped to the carbon-paper carriage. This will create a slack 50 upon 105 which the line-spacing operation of the platen will draw instead of drawing directly from the rolls 7 and 10. If desired, the typist may then move the carbon carriage 25 rearwardly, thus transferring the slack 50 110 to the points 51, adjacent the rolls, thereby laying the webs and the carbon sheets straight at the point 52 from which point the platen will draw directly upon them. Often the weight of the webs behind the 115 cross-bar 58 will thus draw the slack out over the bar.

It will be noted that the construction is such that the pulling forward of the web sheets, or the moving rearwardly of the carbon-paper carriage 25 when the web sheets are held against movement, will swing the clamp arm 36 from its seated position, seen in Fig. 4, to the released position, seen in Fig. 5. In order to limit this throw, the upper end 31 may be provided with a second stop 53 which, when the upper end 31 is swung rearwardly around its pivot 35, will strike against the rear end of the bracket arm 39, and thus prevent the clamp- 125 130

ing arm 36 from being thrown farther from clamping position than the point seen in Fig. 5. This provision insures that the clamping arm 36 will always be near enough the jaw 38 to seize the webs with a small movement relatively thereto, thus practically eliminating any tendency of the clamping member 36 to cause one web to slip upon the other.

10 It has been found sufficient to provide a single clamping arm 36 upon one side of the carbon-paper carriage, and the bracket 40, which forms this member, may be substantially an extension of the edge gage 54, this 15 being for convenience the one adjacent the handle 26.

In order to prevent twisting of the webs during the operations of seizing and letting go of the webs, the usual opposite side gages 20 54 and 55 will be found sufficient, if there are also used the side gages 56 and 57, which are usually placed near each end of the tie bar 58 connecting the rails 30.

The clamping arm 36 seems to work best 25 when its surface is a roll 59 adapted to revolve freely on the arm. Thus the clamp comprises a spring jaw 38 and a roller jaw 36. The depression in the spring jaw advantageously extends only a little beyond 30 the end of the roll 59, with the result that the edge of the spring 38 near the center is flat, and from a point nearer the roller 59, bends sharply down to form the depression 37 in which the roller seats itself. Al- 35 though this wrinkles the webs, it is found that the wrinkles are not sufficient to form permanent creases.

It is found that the clamp 36, 38 grips the webs with sufficient firmness to permit the 40 upper frame 60 of the carbon-paper carriage to be lifted off (Fig. 8) to carry the ends of the webs clear of the carriage, so that another set of webs may be used with another upper frame 60 while preserving 45 the threading and alinement of the carbon sheets. The structure which permits this removal of the upper frame is shown in application No. 175,996, filed June 21, 1917 (now Patent No. 1,358,033, dated November 50 9, 1920).

It is further found that the jaws 36 and 38, if substantially of the form shown in the drawings, will not cause carbon paper interposed between the webs to smut when 55 the jaws seize. This adapts the jaws to be used with other devices, and with webs which utilize carbon surfaces printed on the backs of the webs above. Some typists prefer to operate the devices in a slightly different order, viz., when the parts are in the Fig. 5 position, they push the carbon-paper carriage to the Fig. 7 position and then bring it forward again to the Fig. 5 position, thus creating the slack, so that if the

platens are swung back, the webs will immediately assume the Fig. 9 or 10 position.

The present device is especially adapted to be used in connection with devices for alining the webs preparatory to writing each form. The alining devices may take 70 the form of a pin 68 or pins, adapted to fit in previously punched openings in the webs.

Variations may be resorted to within the scope of the invention, and portions of the improvements may be used without others. 75

Having thus described my invention, I claim:

1. In a typewriting machine, the combination with a revoluble platen about which webs are adapted to be passed, of a clamp 80 adapted to catch said webs, a slide on which the clamp is mounted, and means for automatically making the clamp effective by movement of the slide to a predetermined position.

2. In a typewriting machine, the combination with a revoluble platen about which webs are adapted to be passed, of a clamp 90 adapted to catch and hold said webs, a slide on which the clamp is mounted, said clamp being adapted to be automatically released upon backward movement thereof relative to the webs held thereby, and means whereby the clamp will be rendered effective at the end of its backward movement to cause 95 the webs to be drawn forward thereby.

3. In a typewriting machine, the combination with a revoluble platen about which webs are adapted to be passed, of a clamp 100 adapted to catch said webs, a slide on which the clamp is mounted, and means for automatically making the clamp effective by movement of the slide to a predetermined position, said clamp being adapted to be made ineffective by drawing on the webs to 105 advance it.

4. In a typewriting machine, the combination with a revoluble platen to receive webs passed thereabout, of web-supply means, a clamp for gripping the webs, a slide on 110 which said clamp is mounted, and means whereby the movement of said slide to the rear to a predetermined position will render said clamp effective, said clamp being effective upon forward movement of the slide to 115 advance the webs therewith, and thereby create a slack in the webs between the web-supply means and the platen.

5. In a typewriting machine, the combination with a traveling carriage and a platen 120 revolvably mounted therein, of an extension on said carriage over which a web may be drawn and passed around the platen, a slide adapted to be reciprocated on said extension, a web-gripping clamp connected with said slide to travel therewith, and means for automatically rendering said clamp effective to grip the web by movement of said slide to 125

its limiting rearward position, said clamp being effective when drawn forward with said slide to advance the web upon said extension.

5 6. In a typewriting machine, the combination with a traveling carriage and a platen revolubly mounted therein, of an extension on said carriage over which a web is adapted to be drawn and passed around the platen,

10 a slide adapted to be reciprocated on said extension, a roll from which said web is drawn, a clamp connected with said slide to travel therewith, and means for rendering said clamp effective by movement of said 15 slide to its limiting rearward position, said clamp being effective when drawn forward to advance a web upon said extension to create a slack in the web between the roll and the platen.

20 7. In a typewriting machine, the combination with a rotative platen, of a clamp for seizing and holding webs fed to the platen, said clamp being mounted for forward and backward movement relative to the platen, 25 and means whereby the clamp will be rendered effective to seize and hold the webs at the end of its backward movement, for thereby drawing the webs forward with the clamp, said clamp being adapted to be automatically released upon backward movement 30 thereof relative to the webs held thereby.

8. In a typewriting machine, the combination with a revoluble platen, of means to feed a web to the platen, including a spring 35 having a depression extending inwardly from one side and only partly across the spring, a pivoted arm adapted to swing across said depression, a roller journaled on the end of said arm to fit in the depression 40 and form with the spring a pair of clamping jaws to hold a web, a stop for arresting said arm in its clamping position, a stop for arresting said arm when moved in one direction away from its clamping position, a 45 slide upon which said spring and arm are mounted, and a controlling arm against which the swinging arm is adapted to strike to make the clamp effective and to arrest the slide.

50 9. In a typewriting machine, the combination with a traveling carriage and a revoluble platen therein, of an extension on said carriage, a carbon-paper carriage slideable on said extension, a removable upper frame 55 for said carbon-paper carriage, a clamp upon said frame adapted to grip webs therein, and means for making said clamp effective by movement of the carbon-paper carriage to a predetermined position, to permit the upper frame and the webs associated therewith 60 to be replaced by another upper frame and associated webs.

10. In a typewriting machine, the combination with a traveling carriage and a 65 platen, of a frame in said carriage in which

the platen is adapted to be lifted, feed rolls against which the platen normally bears so that it will hold a web between the platen and the feed rolls, an end gage for gaging the end of a web passed around the platen 70 when the platen is swung up, a roll for the web from which it is drawn, a slide, a clamp upon said slide adapted to be automatically released upon backward movement thereof relative to a web held thereby, and means whereby the clamp will be rendered effective at the end of its backward movement to permit the web to be drawn thereby from the roll to create a slack between the roll and the platen. 75

11. In a typewriting machine, the combination with a revoluble platen and a slide, of a clamp adjustable upon said slide for delivering webs to the platen, and a bracket arm forming part of said clamp forming 80 an edge gage for the webs.

12. In a typewriting machine, the combination with a traveling carriage and a revoluble platen therein, of an extension on said carriage, a slide slideable on said extension, a removable upper frame forming part of said slide, an edge gage adjustably mounted on said frame, and a clamp forming part of said edge gage adapted to seize a web to deliver it by the slide to the platen. 90

13. In a typewriting machine, the combination with a revoluble platen, of a reciprocating slide for feeding a web to the platen, a spring upon said slide, an arm adapted to be swung against said spring to be held there and clamp the web between the arm and the spring, and an adjustable bracket adapted to swing said arm automatically to clamping position. 100

14. In a typewriting machine, the combination with a revoluble platen, of a reciprocating slide for feeding a web to the platen, a spring upon said slide, an arm adapted to be swung against said spring to be held there and clamp the web between the arm 110 and the spring, and an adjustable bracket adapted to swing said arm automatically to clamping position, said arm adapted to be swung to releasing position by drawing upon the web. 115

15. In a typewriting machine, the combination with a spring having a depression extending inwardly from one side and only partly across the spring, of a pivoted arm adapted to swing across said depression, a 120 roller journaled on the end of said arm to fit in the depression and form with the spring a pair of clamping jaws to hold a web, a stop for arresting said arm in its clamping position, a stop for arresting said arm when moved in one direction away from its clamping position, and an adjustable bracket adapted to strike said pivoted arm to make the clamp effective. 125

16. In a typewriting machine, the combi- 130

nation with a revoluble platen about which webs are adapted to be passed, of a clamp adapted to catch said webs, a slide on which the clamp is mounted, and a bracket adjustably mounted for making the clamp effective by arresting the slide.

17. In a typewriting machine, the combination with a revoluble platen about which webs are adapted to be passed, of a clamp 10 for gripping the webs behind the platen, said clamp adapted to bend the paper forming the webs to obtain, without excessive pressure, an effective grip thereon to prevent relative slipping.

15. 18. In a typewriting machine, the combination with a revoluble platen, of a clamp for holding webs behind the platen and forming a gage for the webs, so that the clamp prevents relative movement thereof, 20 and a slide upon which said clamp is mounted.

19. In a typewriting machine, the combination with a revoluble platen, of a clamp for holding webs behind the platen and 25 forming a gage for the webs, so that the clamp prevents relative movement thereof, a slide upon which said clamp is mounted, and connections whereby the clamp is automatically made effective and ineffective.

30. 20. In a typewriting machine, the combination with a traveling carriage and a revoluble platen, of a frame in which said platen is adapted to be lifted to permit webs to be drawn horizontally therebeneath, a gaging 35 device for alining the webs relatively to each other, a slide, and a clamp upon said slide adapted to be automatically made effective at the end of the rearward movement of said slide.

40. 21. In a typewriting machine, the combination with a traveling carriage and a revoluble platen, of a frame in which said platen is adapted to be lifted to permit webs to be drawn horizontally therebeneath, a gaging 45 device for alining the webs relatively to each other, a slide, a clamp upon said slide, and means to render said clamp effective at the end of the rearward movement of said slide, said clamp being adapted to be made 50 ineffective by forward drawing on the webs relatively to the slide.

22. In a typewriting machine, the combination with a traveling carriage and a revoluble platen, of a frame in which said platen 55 is adapted to be lifted to permit webs to be drawn horizontally therebeneath, a gaging device for alining the webs relatively to each other, a slide, a clamp upon said slide adapted to be automatically made effective at the 60 end of the rearward movement of said slide, rails behind the platen upon which said slide runs, and an adjustable bracket fixed relatively to the rails to determine when the clamp shall become effective.

65. 23. In a typewriting machine, the combi-

nation with a traveling carriage and a revoluble platen, of a frame in which said platen is adapted to be lifted to permit webs to be drawn horizontally therebeneath, a gaging device for alining the webs relatively to each 70 other, a slide, a clamp upon said slide adapted to be automatically made effective at the end of the rearward movement of said slide, connections whereby the clamp is automatically made ineffective by drawing on the 75 webs relatively to the slide, rails behind the platen upon which said slide runs, and an adjustable bracket fixed relatively to the rails to determine when the clamp shall be come effective.

24. In a typewriting machine, the combination with a traveling carriage and a revoluble platen, of a frame in which said platen is adapted to be lifted to permit webs to be drawn horizontally therebeneath, a gaging 85 device for alining the webs relatively to each other, a slide, a clamp upon said slide adapted to be automatically made effective at the end of the rearward movement of said slide, rails behind the platen upon which 90 said slide runs, an adjustable bracket fixed relatively to the rails to determine when the clamp shall become effective, and an edge gage adjustably mounted on said slide forming the mounting for the clamp.

25. In a typewriting machine, the combination with a traveling carriage and a revoluble platen, of a frame in which said platen is adapted to be lifted to permit webs to be drawn horizontally therebeneath, a gaging 100 device for alining the webs relatively to each other, a slide, a clamp upon said slide adapted to be automatically made effective at the end of the rearward movement of said slide, connections whereby the clamp is automatically 105 made ineffective by drawing on the webs relatively to the slide, rails behind the platen upon which said slide runs, an adjustable bracket fixed relatively to the rails to determine when the clamp shall become 110 effective, and an edge gage adjustably mounted on said slide forming the mounting for the clamp.

26. In a typewriting machine, the combination with a traveling carriage and a platen 115 revolubly mounted therein, of a roll from which a web is adapted to be drawn to be fed to the platen, a slide between the roll and the platen, a clamp mounted upon said slide to be reciprocated therewith, said clamp being adapted to be automatically released upon backward movement thereof relative to a web held thereby, and means whereby the clamp will be rendered effective at the end of its backward movement, so that a 120 reciprocation of the slide will automatically create a slack in the web between the roll and the platen.

27. In a typewriting machine, the combination with a traveling carriage and a platen 125

- revolubly mounted therein, of a web-supply from which webs may be drawn to be fed to the platen, a slide between the web-supply and the platen, a clamp mounted upon said 5 slide to be reciprocated therewith, said clamp being adapted to be automatically released upon rearward movement thereof relative to webs held thereby, means to render said clamp effective at the end of its 10 rearward movement, so that a reciprocation thereof will automatically create a slack between the web-supply and the platen, and an alining device for alining the webs relatively to each other.
- 15 28. In a typewriting machine, the combination with a bent-over flat spring having a depression extending part way across, of an upright adjacent said spring, an arm pivoted on said upright to swing across the 20 depression and lengthwise of the spring, and a clamping arm extending from said pivoted arm adapted to seat itself in said depression to clamp work-sheets against the depression.
- 25 29. In a typewriting machine, the combination with a bent-over flat spring having a depression extending part way across, of an upright adjacent said spring, an arm pivoted on said upright to swing across the 30 depression and lengthwise of the spring, and a clamping arm having a roller journaled thereon extending from said pivoted arm adapted to seat itself in said depression to clamp work-sheets against the depression.
- 35 30. In a typewriting machine, the combination with a traveling carriage and a revoluble platen therein, of a carbon-paper carriage forming a slide, adjustable edge gages upon said slide, and a clamp upon 40 one of said edge gages adapted to seize one edge of a plurality of sheets passing between said gages.
31. In a typewriting machine, the combination with a traveling carriage and a 45 revoluble platen therein, of a carbon-paper carriage forming a slide, adjustable edge gages upon said slide, a clamp upon one of said edge gages adapted to seize one edge of a plurality of sheets passing between said 50 gages, an adjustable bracket, and an arm forming part of said clamp to control the effectiveness thereof and adapted to strike said bracket to arrest the slide.
32. In a typewriting machine, the combination with a traveling carriage and a 55 revoluble platen, of a slide over which webs pass to said platen, a clamp mounted upon said slide adapted to seize the webs, said clamp adapted to release the webs when the 60 webs are drawn upon, an upstanding arm forming part of the clamp, a rail upon which the slide runs, and an adjustable bracket comprising an arm extending horizontally to intercept said bracket arm to make the 65 clamp effective and to arrest the slide.
33. In a typewriting machine, the combination with a traveling carriage and a revoluble platen, of a carbon-paper carriage 70 slidable upon the typewriter carriage and adapted to have carbon sheets made fast thereto, so that the carbon sheets may be interleaved between webs, a clamp for clamping the webs to the carbon-paper carriage to preserve the relationship between the carbon sheets and the webs, and means whereby 75 movement of said carbon-paper carriage to a predetermined position will render said clamp effective.
34. In a typewriting machine, the combination with a traveling carriage and a 80 revoluble platen, of a carbon-paper carriage slidable upon the typewriter carriage and adapted to have carbon sheets made fast thereto, so that the carbon sheets may be interleaved between webs, a clamp for automatically clamping the carbon carriage to the webs to preserve the relationship between the carbon sheets and the webs, rolls 85 from which said webs are drawn, and a handle for oscillating said carbon-paper carriage to create a slack in the webs between the rolls and the platen.
35. In a typewriting machine, the combination with a traveling carriage and a revoluble platen, of a carbon-paper carriage 90 slidable upon the typewriter carriage and adapted to have carbon sheets made fast thereto, so that the carbon sheets may be interleaved between webs, and a clamp for automatically clamping the carbon carriage 95 to the webs to preserve the relationship between the carbon sheets and the webs, said carbon-paper carriage having a removable top upon which the carbon sheets and clamp are mounted to permit another removable 100 top having other webs clamped thereon to be substituted therefor.
36. In a typewriting machine, the combination with a traveling carriage and a revoluble platen, of a carbon-paper carriage 110 slidable upon the typewriter carriage and adapted to have carbon sheets made fast thereto, so that the carbon sheets may be interleaved between webs, a clamp for automatically clamping the carbon carriage to 115 the webs to preserve the relationship between the carbon sheets and the webs, rolls from which said webs are drawn, and a handle for oscillating said carbon-paper carriage to create a slack in the web between 120 the rolls and the platen, said carbon-paper carriage having a removable top upon which the carbon sheets are mounted to permit another removable top having other webs clamped thereon to be substituted therefor. 125
37. In a typewriting machine, the combination with a traveling carriage and a revoluble platen, of a frame in which said platen is adapted to be lifted to permit webs to be drawn horizontally therebeneath, a 130

gaging device for alining the webs relatively to each other, a slide, and a clamp upon said slide adapted to be automatically made effective at the end of the movement 5 of said slide.

38. In a typewriting machine, the combination with a traveling carriage and a revoluble platen therein, of a carbon-paper carriage forming a slide, adjustable edge 10 gages upon said slide, a clamp upon one of said edge gages adapted to seize one edge of a plurality of sheets passing between said gages, an adjustable bracket, and an arm forming part of said clamp to control the 15 effectiveness thereof and adapted to strike said bracket.

39. In a typewriting machine, the combination with a traveling carriage and a revoluble platen, of a slide over which webs pass to said platen, a clamp mounted upon 20 said slide adapted to seize the webs, said clamp adapted to release the webs when the webs are drawn upon, an upstanding arm forming part of the clamp, a rail upon which the slide runs, and an adjustable 25 bracket comprising an arm extending horizontally to intercept said bracket arm to make the clamp effective.

JESSE A. B. SMITH.
